(57) **CLAIM**

The ornamental design for a winder of launching apparatus for spinning top toy as shown and described.

DESCRIPTION

FIG. 1 is a front elevational view of a winder of launching apparatus for spinning top toy, showing the new design; FIG. 2 is a rear elevational view thereof; FIG. 3 is a left-side elevational view thereof; FIG. 4 is a right-side elevational view thereof; FIG. 5 is a top plan view thereof; FIG. 6 is a bottom plan view thereof; FIG. 7 is a front, right-side, top perspective view thereof; FIG. 8 is a rear, left-side, bottom perspective view thereof; and, FIG. 9 is a reference perspective view showing a state of use. The broken lines depict environment and form no part of the claimed design.

1 Claim, 9 Drawing Sheets
